UNITED STATES PATENT OFFICE

143,661

DESIGN FOR A FLUID AGITATING AND MIXING RECEPTACLE OR SIMILAR ARTICLE

Gebhard W. Keny, Columbus, Ohio, assignor to Columbus Plastic Products Inc, Columbus, Ohio, a corporation of Ohio

Application August 1, 1945, Serial No. 121,145

Term of patent 14 years

(Cl. D44—1)

To all whom it may concern:

Be it known that I, Gebhard W. Keny, a citizen of the United States, residing at Columbus, in the county of Franklin and State of Ohio, have invented a new, original, and ornamental Design for a Fluid Agitating and Mixing Receptacle or Similar Article, of which the following is a specification, reference being had to the accompanying drawing, forming a part thereof.

Fig. 1 is a top plan view of a fluid agitating and mixing receptacle or similar article showing my new design;

Fig. 2 is a perspective view thereof.

I claim:

The ornamental design for a fluid agitating and mixing receptacle or similar article, as shown.

GEBHARD W. KENY.
